(57) **CLAIM**

The ornamental design for a tank and side cover assembly for a motorcycle, as shown and described.

DESCRIPTION

FIG. 1 is a perspective view of the tank and side cover assembly for a motorcycle.

FIG. 2 is a perspective view from the right side thereof.

FIG. 3 is a perspective view from the left side thereof.

FIG. 4 is a perspective view from the right side thereof.

FIG. 5 is a front elevation view thereof.

FIG. 6 is a rear elevation view thereof.

FIG. 7 is a left side elevation view thereof.

FIG. 8 is a right side elevation view thereof.

FIG. 9 is a top plan view thereof; and,

FIG. 10 is a bottom plan view thereof.

The broken lines shown in the drawings are for the purpose of showing environmental structure only and form no part of the claimed design.
